UNITED STATES PATENT OFFICE

2,151,545

COMPOSITE BIT

John A. Zublin, Los Angeles, Calif.

Application July 11, 1938, Serial No. 218,491

5 Claims. (Cl. 255—73)

The present invention relates generally to rotary well drilling bits such as are used to drill oil wells and the like, and more particularly to drill bits of the general type described in my prior United States Patent Nos. 2,050,988 and 2,069,799. Drill bits of this type are provided with a plurality of rotatable cutters mounted upon one or more carriers which, in turn, are rotatably mounted upon a shank. Because of this type of mounting the reaction of the cutters on the formation causes the carrier to rotate with respect to the shank and thereby successively and intermittently cause the rollers to contact with the formation with a rolling motion thereon. The general principles underlying the type of drill bit under consideration will be found in my Patent No. 2,050,988.

In the first mentioned patent, a plurality of carriers is used, the cutters on each carrier contacting the bottom of the hole on opposite sides of the bore axis. This arrangement prevents any of the cutters from coming into coincidence with the axis of the hole when the cutters are in their bottommost position. The second mentioned patent (No. 2,069,799) is provided with only a single carrier which is preferably inclined to the horizontal. The inclination will normally cause the bottommost roller to contact with the formation to one side of the hole axis and will thereby insure rotation of the carrier about the inclined axis so long as the shank is being rotated.

In view of the fact that drill bits of the type under consideration form a hemispherical bottom in the formation, drilling weight on the bit would tend to move the bottommost roller into coincidence with the hole axis. If this were to occur, rotation of the carrier in the manner aforementioned would practically cease. To overcome this possibility it has heretofore been proposed to provide a thickened leg portion on the shank which will bear against the sides of the hole and prevent the bottommost roller from moving into a position coincident with the hole axis. The thickened leg portion is an effective instrumentality for insuring carrier rotation. But it also introduces wear on the leg caused by its thrust against the formation. It is with the end in view of decreasing or eliminating the wear on the shank, as the leg portion thereof, and in maintaining the bottommost roller from coincidence with the hole axis that the present invention is concerned.

Accordingly, it becomes a general object of this invention to provide an improved drilling bit specially adapted for use in hard formations.

A further object of the invention resides in the provision of an improved bit having separated digging and reaming portions.

A further object of the invention involves a bit in which the side thrust on a shank is absorbed by reaming rollers.

Still another object of the invention is to provide a bit wherein the bottom contacting rollers are maintained to one side of the hole axis by upper reaming rollers.

A further object of the invention lies in the provision of a bit which will be self-stabilizing in the hole and which will prevent the production of an undergauged bore.

A further object of the invention lies in the provision of improved flow channels for maintaining reaming rollers free from cuttings while at the same time assisting their rotation about their own respective axes.

In the prior art constructions, roller reaming cutters have usually been disposed equidistant circumferentially of their supporting shank. When two diametrically opposite cutters are used, the reamer is capable of wobbling and possesses unsteadiness in its operation. On the other hand, when three or more equidistant rollers are used, the reamer possesses stability but has associated with it a restricted clearance which in some instances will prevent operation of the tool, as when it is necessary to pass through collapsed casing.

Accordingly, it becomes a further object of this invention to provide a rotary reamer that is more stable in operating in the bore hole.

A further object of the invention involves a rotary reamer having increased clearance, rendering it more readily passable through a bore hole or casing.

Still another object of the invention involves a nonuniform disposition of roller reaming cutters around the circumference of the shank to provide a bit possessing stability in its operation and capable of producing a full gauge hole.

How the above and other objects and advantages of my invention are secured will be better understood by reference to the following description and the annexed drawing in which:

Figure 1 is an elevation of the composite bit with parts thereof being shown in section;

Figure 2 is a side elevation of the drill bit as seen from the right of Figure 1;

Figure 3 is a section along the line 3—3 of Figure 1; and

Figure 4 is a view similar to Figure 3, on a reduced scale, showing a modified form of reamer.

In general, the drill bit includes a lower cutting portion A and an upper reaming portion B. The former is substantially the same as that described in my copending application entitled "Compact bits" filed February 21, 1938, Serial No. 191,622. Inasmuch as it is not by itself being claimed in this application the various parts and the advantages of the arrangement shown will not be described in particular detail.

The lower portion of the bit includes a plurality of depending legs 11, 12 extending from the shank body 10, the upper end of which carries the usual threaded pin 13 for connecting the drill bit with the drilling string. One of the legs 11 has formed integrally therewith a bearing supporting member 14 adapted to carry a cutter assembly C, to be described hereinafter. The end of the bearing supporting member 14 is provided with a reduced extension 15 fitting into a bore 16 formed in the leg 12 of the shank, which leg, after the cutter assembly has been placed on the bearing supporting member, can be welded at its upper end 12a to the shank body proper and at its lower region 12b to the reduced extension 15. The cutter assembly includes a cutter carrier 17 provided with a plurality of circumferentially spaced slots 18 which are bridged by bearing pins 19 welded to the side portions 20 of the slots, each pin carrying one or more formation 30 contacting rollers 21. The carrier 17 is provided with a plurality of ball bearing raceways 22 in an inner bore 23, which are adapted to cooperate with an inner bearing race 24 containing complementary toric raceways 25. Between the raceways are provided balls 26 which will serve to transmit bearing loads between the carrier and inner race.

Prior to the placing of the separate long leg 12 on the reduced bearing supporting extension 15 and its welding thereto and to the shank body, the carrier 17 with the cutters 21 and pins 19 thereon is placed over the inner race 24 and the bearing balls 26 introduced into the raceways 22, 25 through the holes 27 formed within the inner race and communicating with respective raceways. Thereafter, buttons 28 having an upper cylindrical portion 28a and a lower rectangular portion 28b are inserted into the bores, serving to prevent the balls from falling from the raceway while at the same time providing a substantially continuous raceway on which the balls can roll as the carrier rotates. The lower portion 28b of the buttons is made rectangular in shape so as to be capable of riding in the keyway 29 formed in the bearing supporting member, and thus serving to lock the inner race 24 from rotation with respect to the bearing supporting member 14. As explained in my application above referred to, the buttons serve the three-fold function of providing a substantially uninterrupted raceway, preventing the balls from falling from the raceway, and keying the inner raceway to the bearing supporting member.

Upon assembly of the carrier 17 on the main bearing and the insertion of the buttons 28 in the manner aforementioned, this entire assembly is slid over the bearing supporting member with the rectangular button heads riding in the keyway. Thereafter, the long leg 12 is placed over the reduced extension 15 with the boss 30 on the leg abutting the end of the inner race, and causing the opposite end of the race to abut against the boss 31 formed on the other leg 11 extending from the shank. Upon welding the upper part of the leg 12a to the shank 10 and the

lower part to the reduced extension 15, a rigid shank assembly results for carrying the cutter assembly for rotation with respect to the shank about an inclined axis D—D with the bottom-most roller 21a positioned to one side of the axis E—E of the hole.

As described in my copending application, an upper nozzle 32 is placed in the shank communicating with and receiving drilling fluid from the passageway 33 provided in the shank. The nozzle 10 will effect a discharge of fluid against successive cutters as they pass under it, the force of the fluid rotating each cutter about its own axis to insure that all of the teeth or cutting edges are effectively cleaned. The cuttings are removed 15 from the bottom of the hole by discharge of fluid from a nozzle 34 threadedly held in the lower portion of the leg 11 which has a conduit 35 therein for establishing communication between the shank passageway 33 and the nozzle 34. The 20 fluid will issue from this lower nozzle and sweep transversely across the hole bottom for effectively removing the detritus.

The upper portion B of the bit constitutes a reamer. A plurality of slots 36 is formed in the 25 shank body with the ends of each slot terminating in a plurality of notches or grooves 37, each of which receives a bearing pin 38. Each bearing pin carries one or more reamer roller cutters 39a, 39b having teeth thereon, although, if desired, 30 disc or other cutters can be used. The rollers in each set are mounted upon their pin, which is then inserted in the notches 37 of the shank. The ends of the pins are welded in the groove to effect a rigid attachment of the pins to the 35 shank body while permitting free rotation of the rollers on the pins. In the specific illustration shown in Figures 1 and 3 a set of rollers is provided on one portion of the shank, being balanced by a substantially diametrically opposite single roller. However, the number of rollers may be varied without departing from the scope and spirit of the invention relating to the combination of the lower cutting portion and reaming portion.

One of the main features of the invention resides in positioning the rollers 39a at the right of the drill bit (as seen in Figure 3), so that by their contact with the formation they will maintain the bottommost rollers 21a at the lower portion of the bit from coincidence with the hole axis. That this will occur will become apparent from a mere inspection of Figures 1 and 3. As the drilling tool rotates, the reaming rollers will move around on the formation, maintaining the hole to gauge, and because of their engagement with the sides of the hole will position the bottommost rollers 21a to the side of the hole axis opposite to the position of the reamer rollers. It will be noted further that 60 the shank leg 12 is spaced from the sides of the hole, and will be maintained in the spaced position by the engagement of the upper reamer rollers 39a with the formation throughout substantially the entire drilling life of the tool. This 65 will prevent wear from occurring on this leg, or decrease the wear. Similarly, wear upon the other leg 11 depending from the shank will be prevented by the other set of rollers 39b which, by their contact with the sides of the hole, will 70 maintain this leg spaced from the formation.

As stated before, the number of reamer rollers can be varied. Thus, even a single roller, or a single set positioned on that side of the hole axis opposite to the position of the bottommost 75

hole contacting roller 21a will maintain such contacting position and eliminate wear upon the long leg 12 depending from the shank. Moreover, one or more larger or smaller diameter 5 reamer rollers can be used to alter the contact position of roller 21a as regards the hole axis, and also to change the final diameter of the bore.

The reamer rollers are kept free from cuttings 10 by the incorporation of a plurality of nozzles 40a, 40b threaded into the shank and communicating with the passageway 33 in the shank body. Fluid will issue from the small nozzles and engage against all parts of each roller cutter since 15 each cutter will rotate about its bearing pin and during this movement will position all of its cutting parts in the path of the stream issuing from the nozzle. Each nozzle is positioned so as to direct its discharge to one side of the axis of 20 the roller upon which it acts in the direction of rotation of the roller. The leading roller 39a on one side of the shank as regards rotation of the bit will have an inclined fluid stream issuing from the nozzle 40a. By virtue of this design 25 the fluid streams tend to assist rotation of each roller about its axis and at the same time thoroughly flushes all cutting parts thereon.

Apart from its novel mode of operation in conjunction with the lower cutting portions of 30 the drilling tool, the reamer arrangement shown possesses certain advantages when considered alone. It will be noted that the rollers 39a are adjacent one another circumferentially of the shank, and that the roller 39b is substantially 35 diametrically opposite the first named pair. By this arrangement an increased clearance between the shank and the walls of the bore and casing can be had when compared with a reamer construction in which three rollers are spaced equidistant circumferentially of the shank, or 120° 40 apart; or when compared with equidistant spacing of more than three cutters. While the use of two diametrically opposite rollers is known, such types of reamers are unstable since they 45 can oscillate or wobble about a line passing through their contacting positions with the formation. The arrangement disclosed in Figure 3 not only provides an increased clearance, but also stabilizes the tool by virtue of its three-point contact with the walls of the hole. 50 The modification disclosed in Figure 4 also provides stability and an increased clearance, although not to so great an extent as the Figure 3 construction. In Figure 4, four rollers are disclosed. But instead of being disposed equidistant circumferentially of the shank, or 90° apart, the rollers 39a are moved toward one another so as to occupy circumferentially adjacent positions on the shank. The other rollers 55

39b occupy a position of substantially 90° with respect to one another, their median plane being placed substantially diametrically opposite the median plane of the rollers 39a. As a result, the circumferential distance between the rollers 5 39a and 39b is much greater than the circumferential distance between each roller 39b of the pair position 90° apart.

In the Figure 4 arrangement, the nozzles 40a and 40b are disposed in a similar manner as in 10 the Figure 3 arrangement, their lines of discharge passing to one side of the axes of the rollers in order to assist their rotation.

This application is a continuation in part of my application Serial No. 191,621, filed February 15, 1938, Composite bits.

While the invention has been described with particular reference to the embodiment shown on the drawing, it is to be understood that changes may be made in its construction and 20 arrangement of parts without departing from the intent and scope of the invention, and consequently, the foregoing description is to be considered illustrative of rather than restrictive upon the claims appended hereto. 25

I claim:

1. A reamer comprising a shank, a pair of roller reaming cutters on the shank, the cutters of said pair being in adjacent relation circumferentially of said shank, and a roller reaming 30 cutter positioned on the shank substantially diametrically opposite said pair of cutters.

2. A reamer comprising a shank, three roller reamer cutters on the shank including a pair of cutters in adjacent relation circumferentially of said shank and a third cutter substantially diametrically opposite said pair of cutters.

3. A reamer comprising a shank, a pair of roller reaming cutters on the shank, the cutters of said pair being in adjacent relation circumferentially of said shank, and a second pair of reaming cutters on the shank opposite said first pair and spaced a greater circumferential distance apart than said first-mentioned pair.

4. A reamer comprising a shank, one or more roller reaming cutters on the shank, a fluid passageway in said shank, and fluid discharge means communicating with said passageway and arranged on the shank to direct its discharge against the reaming cutter to one side of its axis whereby to urge its rotation.

5. A reamer comprising a shank, a roller reaming cutter on the shank, a fluid passageway in the shank, and a nozzle positioned on the shank so that the fluid discharge therefrom will be directed against the cutter to one side of its axis whereby to urge its rotation.

JOHN A. ZUBLIN.
